UNITED STATES PATENT OFFICE.

WALTER P. MURPHY, OF CHICAGO, ILLINOIS, ASSIGNOR TO UNION METAL PRODUCTS COMPANY, OF CHICAGO, ILLINOIS; A CORPORATION OF DELAWARE.

END WALL STRUCTURE FOR RAILWAY CARS.

Application filed December 30, 1922. Serial No. 609,868.

To all whom it may concern.

Be it known that I, WALTER P. MURPHY, residing at Chicago, county of Cook, State of Illinois, and being a citizen of the United States, have invented certain new and useful Improvements in End Wall Structures for Railway Cars, of which the following is a full, clear, and exact description, such as will enable others skilled in the art to which

it appertains to make and to use the same, reference being had to the accompanying drawings, which illustrate the preferred form of the invention, though it is to be understood that the invention is not limited 10 to the exact details of construction shown and described, as it is obvious that various modifications thereof within the scope of the claims will occur to persons skilled in the art.

20 My invention has for its object to provide a metal car construction of novel character which is unusually strong for its weight and durable throughout, which may be conveniently and economically manufactured 25 and transported, is weatherproof and which possesses certain other desirable and advantageous features to be hereinafter described and claimed.

The ends of railway cars are subject to considerable stress due to the shifting of the lading. These blows may be imparted to the end over the entire area thereof, or to local or concentrated areas. Corn is loaded to substantially the top of the car which causes the blow to be imparted over the entire area of the end. Lumber is loaded to the top and upon impact the top boards shift causing a blow to be imparted at the top of the end. Sand, chats and other plastic loads and light pipe cause blows at the middle of the car, whereas rails, steel plates, castings and the like cause blows at the bottom of the car. From the above it will be apparent that a railway car end 40 must be very strong throughout its entire area.

While, of course, efforts are made to block the lading in the car, the heavy locomotives, the emergency air brake and the classification hump, break the lading away from its moorings and throw it against the end of the car.

50 A rigid end to a car, and particularly a large box car, materially strengthens the entire superstructure to resist the torsional

and weaving movements which not only rack the car to pieces, but cause leaky roofs and inoperative and leaky doors with their consequent damage claims. As it costs as much to transport a ton of freight car as 60 it does a ton of lading it is imperative that the weight of the car must be kept as low as possible, therefore, the end must be very light as well as strong. As freight cars are frequently damaged in wrecks and by other 65 unfair usage, any end may be damaged in service, therefore, it must be capable of being easily repaired with such meagre facilities as the railroads are equipped with at their outlying repair points. 70

Corrugated steel ends are now extensively used wherein the corrugations terminate within the edge of the sheet which requires considerable stretching of the metal to form such corrugations. The plates must be 75 heated and placed under powerful hydraulic presses, and as there are very few presses in the United States large enough to do this work, the field for producing such ends is limited. Furthermore, such ends must be 80 trimmed to a rectangular shape after pressing before they can be applied to a car, thus causing a waste of material. (The process of manufacturing such a plate is described in Sisson Patent No. 1,271,234 of 85 July 2, 1918.)

In Murphy Patents No. 1,186,493 of June 6, 1916, and No. 1,236,744 of August 14, 1917, it was proposed to use a corrugated wall plate in which the corrugations extended 90 to the edge of the sheet and are secured to the car by angles having one flange corrugated or serrated which fit into and are secured to the corrugations of the wall plate, thus producing a weatherproof construction at the corner of the car. These corrugated angles require heating and pressing which is expensive; furthermore, it is difficult to obtain a fit between the corrugations of the angles which are hot 95 pressed, and the corrugations of the wall plate, which are cold rolled, because the heated steel is subject to variable contraction in cooling while the cold steel is subject to variable stretching when run through the fluted rolls. Contraction and stretching are dependent upon the carbon content of the steel and other chemical properties. 100

One of the objects is to obtain an end wall 105 wherein the end, as well as the attaching

members, may be formed cold, thus reducing cost of manufacture considerably and expediting delivery, and making it practicable to use a plate wherein the corrugations extend to the edge thereof.

As steel specialty companies specialize in producing certain classes of work it is desirable to have an end in which the parts can be produced in separate places and yet 10 easily assembled, without heating, or necessitating any special machinery, after they arrive at the railroad shop or place of assembly.

Another object is to obtain an end for a 15 car which can be economically assembled in the field or bench and carried to the car as an integral unit.

I have shown and described my improvement with the corrugations positioned horizontally but they may be positioned vertically or obliquely. Furthermore, the wall may be made of one or a plurality of plates connected along horizontal, vertical or oblique lines. Furthermore, the construction 20 may be applied to the side or end wall of a box, gondola, or any other type of railway car, or the cross sectional contour of the corrugations may be of any desired contour.

In the drawings:

30 Fig. 1 shows the end elevation of a box car with my invention applied thereto.

Fig. 2 is a section drawn along the line 2—2 of Fig. 1.

Fig. 3 is a section drawn along the line 35 3—3 of Fig. 1.

Fig. 4 is a cross section on a horizontal plane through the corner post of the car.

Fig. 5 is a perspective view of the serrated plate.

40 Fig. 6 is a perspective view of the serrated attaching plate having integral flanges.

Fig. 7 is a fragmentary elevation of the side of the corner post.

Fig. 8 is a cross section along line 8—8 of 45 Fig. 7.

Numeral 1 shows a plate having corrugations or strengthening formations formed therein extending from one edge of the plate to the other; 2 shows the end sill angle; 3 the end plate flange; 4 the center sills; 5 the striking casting; 6 the end and side sill connection gusset; 7 the end lining; 8 the floor; 9 the corner post; 10 the side sheathing and 50 11 the inside side lining, all of which are 55 the usual parts of a car of this nature.

An attaching plate 12 is secured to the side wall or corner post of the car by bolts 13 and other convenient means, which attaching plate has the forward edge serrated or cut to conform to the contour of the corrugations of the reinforced plate, as shown in Fig. 5. These attaching plates may be merely slit and the alternate portions between the slits bent over to form attaching flanges, which flanges are riveted to the metallic panel. This construction is shown in Fig. 6. Angles may be riveted to the portions between the flanges for connecting it to the metallic panel, which is also shown in Fig. 6 by dotted lines.

If the flat serrated plate is used, as shown in Fig. 5, connecting angles may be used to secure the attaching plate to the metallic panel, as shown in Figs. 7 and 8.

It may be desirable to use a flat attaching plate and allow the metallic panel to abut into it, as shown in Figs. 7 and 8, in which construction connecting angles will be used to secure the attaching plate to the metallic panel.

What I claim is:

1. In a metallic wall for railway cars comprising a flat attaching member serrated at one edge having the portions between the serrations bent to form connecting flanges, a metal panel having corrugations formed therein extending to opposite edges of said panel, the serrations of said attaching member fitting into said corrugations; and said flanges secured to said panel.

2. In a metallic wall for railway cars comprising a flat attaching member serrated at one edge having the portions between the serrations bent to form connecting flanges, a metal panel having corrugations formed therein extending to opposite edges of said panel, the serrations of said attaching member fitting into said corrugations, said flanges secured to said panel, and additional means connecting said serrations to said panel.

3. In a metallic wall for railway cars comprising a metallic panel having corrugations formed therein extending to the opposite edges of said panel, a flat attaching member having serrations at one edge fitting into said corrugations, and separate means securing the serrations to the panel.

WALTER P. MURPHY.
